TWIN TRAY CARRIER

Alan Bedol, Shaker Heights, Ohio, assignor to The Marshallan Manufacturing Company, Cleveland, Ohio,
a corporation of Ohio

Filed Feb. 28, 1962, Ser. No. 69,028

Term of patent 14 years

(Cl. D14—6)

FIGURE 1 is a perspective view of a twin tray carrier showing my new design, in open position, with the portions shown in broken lines being included for illustrative purposes only; and

I claim:

The ornamental design for a twin tray carrier, substantially as shown and described.
